LEES W. CHADWICK, OF ROYAL OAK, MICHIGAN, ASSIGNOR OF ONE-HALF TO
CHARLES R. LE CLAIR, OF DETROIT, MICHIGAN.

ART OF PRODUCING BEARINGS, BUSHINGS, &c.

1,359,331.

Specification of Letters Patent. Patented Nov. 16, 1920.

Application filed June 23, 1919. Serial No. 305,948

To all whom it may concern:

Be it known that I, LEES W. CHADWICK, a citizen of the United States of America, residing at Royal Oak, in the county of 5 Oakland and State of Michigan, have invented certain new and useful Improvements in the Art of Producing Bearings, Bushings, &c., of which the following is a specification, reference being had therein to 10 the accompanying drawings.

This invention relates to improvements in the art of producing bearings, bushings, etc., pertaining more particularly to the production of articles of this type made 15 from the softer metals and which may or may not include a Babbitt metal face.

The production of articles of this general type becomes difficult when an attempt is made to provide production under capacity 20 conditions, especially where the Babbitt metal lining is of comparatively small cross section so as to approach the conditions of a thin skin or film—for instance, the thickness of one-thirtysixth inch. When, however, the requirements of use of the article 25 are such as to place additional conditions or inspection tests on the completed article, the difficulties are vastly increased. For instance, the accuracy of the active face or 30 faces of the article becomes of great importance where the article is used in connection with comparatively-high speed operations, in which case the presence of a high point or points on said face is an absolute cause of rejection, due to the fact 35 that under such conditions, the face is designed to be bathed in oil or other lubricant, and the presence of such high point or points prevents perfect lubricating effect.

Another feature or condition is that of interchangeability, a condition which necessitates at times the production of a required 40 number of articles with the limit of difference allowable less than .0005 inch. The 45 limits allowed in connection with the bearings and the bushings of the Liberty motor manufactured in accordance with the methods herein disclosed were .0003 inch; production under conditions of this 50 severity in order to permit interchangeability of bearings without individual treatment of each bearing or bushing with respect to the part with which it co-operates, is obviously of great difficulty.

In addition to these problems, the ques-

tion of producing the article at comparatively low manufacturing cost is of great importance. And this is especially true in connection with quantity production where the controlling conditions have the severity 60 above indicated. While it might be possible to meet the severe conditions of tests through careful hand and machine operations—although the comparatively thin Babbitt metal face, when used, becomes an 65 additional problem when attempting to operate under such conditions the cost of production becomes so burdensome as to make it practically prohibitive where the attempt is made to provide for interchangeability. 70

Attempts of various kinds have been made to meet these objections, but these have generally been unsuccessful by reason of the problems presented and additionally because of the fact that in many of the attempts it becomes necessary to waste a large amount of the metal from which initial blank is produced, either resulting in an actual waste of the metal or the necessity for re-melting or re-treating the waste 80 metal to permit its re-use; in either case the cost of production is largely increased.

The present invention is designed to generally overcome these difficulties and meet the problems in such a way as to permit of 85 quantity production at comparatively low cost of manufacture and at the same time provide the characteristic of interchangeability between similar articles so as to avoid individual treatment.

To these and other ends, therefore, the 90 nature of which will be readily understood as the invention is hereinafter disclosed, said invention consists in the improved methods of production, and the article produced, as more fully described hereinafter, illustrated in the accompanying drawings, and more particularly pointed out in the appended claims.

In the accompanying drawings in which 100 similar reference characters indicate similar parts, in each view,—

Figures 1 to 3 inclusive are views showing in end elevation successive developments in the production of a blank from 105 which the article is produced;

Fig. 4 is a similar view indicating the manner in which the embryo article is produced from the blank;

Fig. 5 is a plan view of one form of ap-

110

paratus for providing a stage development of the embryo article;

Fig. 6 is a front elevation of the structure of Fig. 5, parts being omitted for clearness;

Fig. 7 is an end view, on an enlarged scale, of an anvil employed in the apparatus of Fig. 5;

Fig. 8 is a plan view of one form of shaping apparatus which may be employed in a later stage of the article development, the apparatus being shown in a position before the shaping is completed;

Figs. 9 and 10 are sectional views taken on the lines 9—9 and 10—10 respectively of Fig. 8;

Fig. 11 is a plan view of the plate employed in the apparatus of Fig. 8; and

Fig. 12 is a perspective view of the completed article.

Before giving a detail description of the method disclosed herein, a few of the problems involved in the production of bearings, etc., under quantity conditions will be referred to.

Since the members of a bearing must have the active face corresponding with the circumference of a circle of proper radius, the simplest form of blank is one which is circular in contour. A blank of this type can be readily machined into proper dimensions, but if the attempt be made to provide these dimensions in correspondence with those of the completed article, the necessity for dividing the blank into halves to produce the bearings, introduces a material factor in that the tool for dividing the blank has inevitably a thickness such as will affect the true circular contour of the two halves if the mating faces are brought into contact; this

for the reason that the material removed from the blank during the cutting operation affects the contour and destroys the true circular form. Under present practice, where this general method is employed, this

particular condition is met by the introduction of a shim between the two halves and having a thickness corresponding to the thickness of the material removed during the dividing operation. This inherently re-

quires an individual treatment of each bearing, since each pair must be adjusted to produce the proper circular contour. This is one of the factors which tends to affect the ability to provide for interchangeability.

Attempts have been made to meet these conditions by producing a special blank in which the diameters at right angles to each other are different, the difference being sufficient to accommodate or compensate for the material removed during the dividing action. This is more or less unsatisfactory and expensive, due to the difficulty of attempting to machine the faces to proper sizes and the necessity for absolute accuracy in the selection of diameter on which the di-

viding line is made. The present invention meets the several problems by a practice involving several stages which enables the machining operations, etc., which involve the faces of the bearings, to be provided under normal conditions, but entailing a minimum expense in manufacture with respect to the machining operations and permitting the production to proceed under comparatively high capacity conditions. This result is obtained by forming the blank truly cylindrical and finishing it so far as the thickness of the walls of the bearing are concerned while in the blank form, thus completing the faces of the bearings in such manner as to require no further machining operations. The production of the blank may involve several stages, especially where the article is to be of extreme accuracy; these stages, however, may be varied in accordance with the particular requirements in the accuracy, etc., of the article, but one of the essentials of the method as now practised by me—and which is preferred although not wholly essential—is that the machine operations are preferably completed while the material of the bearing is in the blank cylindrical form.

One of the essentials of the invention is that the blank when completed by passing through the several stages of the operation will have its inner and its outer faces of greater radii than the completed article, the difference in radius of the two diameters, however, corresponding to the similar difference in the completed article, thus having the thickness of the wall of the blank corresponding to the thickness of the wall of the completed article. The excess diameters of the blank over the similar dimensions of the bearings will, of course, vary with the particular size and shape of the bearings or other article. No particular rule for determining the excess can be set forth since the variations in general conditions of materials, thickness of walls, etc., necessarily affects said diametrical dimensions.

For the purpose, however, of presenting an example, I will hereinafter set forth the several stages and measurements employed in the production of the short main bearings for the Liberty motor, these bearings having an external radius of one and one half inches (being known as a three inch bearing,) this bearing being Babbitt lined and having a thickness of wall in a completed article of .1851 inch, the length of the bearing being 1.968 inches.

The successive stages in producing the blank of the bearing referred to—the three inch bearing of the Liberty motor—includes the following:

Cast the bushing of bronze of a size to include the different dimensions. Bore the bushing to a diameter of 2.780 inches; this produces the face which is to be Babbitt

lined. Rough turn the outer face of the bushing to 3.065 inches diameter; this provides an approximate blank, shown in Fig. 1 in end view, the blank being indicated as 5 A, the different diameters being indicated. Babbitt the bushings. Cut off the gate and bore the Babbitt to 2.650 inches diameter. Turn the outside diameter to 3.035 inches and cut the bushing to a length of 1.968 10 inches; this produces the approximate blank, the dimensions of which are indicated in Fig. 2 of the drawings, the Babbitt being indicated at B. The blank of Fig. 3 has been completed by first broaching the Babbitt lining to diameter of 2.6555 inches, and grinding the outside diameter of the bushing to 3.0257 inches. This provides inner and outer diameters of the Babbitt lined bushing larger than those required in the 15 completed bearings—the latter having an external radius of 1.5 inches and an interior radius of 1.3149 inches—with the thickness of the wall .1851 inches, this thickness being the same in the completed bearings and 20 in the blanks, the latter being shown in finished form in Fig. 3.

The blank is then divided diametrically, as shown in Fig. 4. In the particular example referred to this dividing was provided 30 by a saw having a cutting width of one-thirty-second inch. As will be understood, the dividing has the effect of reducing the segmental length an amount substantially equal to the thickness of the saw—the same 35 reduction being made on the points of intersection with the saw of the cylinder blank, the material removed in providing the cut, obviously being equal to two thicknesses of the saw, or the total decrease in the length of 40 the cylinder circumferentially of one-sixteenth inch.

The division of the blank into its two halves produces duplicate segments, each of which is designed to produce one of the 45 halves of a bearing. In the subsequent operations each of these segments is treated individually, but all segments have the same treatment. In the particular example referred to, the bearings were required to pass 50 an inspection in which limits of difference were limited to .0003 inch, this condition being employed in order that bearings may be used interchangeably with assurance of meeting the onerous conditions of service.

55 The completion of the bearing is had by subjecting the embryo formation thus produced to an operation or operations designed to change the radii of the inside and outside faces of the embryo formation, this being 60 had without affecting the thickness of the segment wall or disturbing the faces which were prepared in the original blank form. In the example indicated this result was obtained by the use of three operations and two 65 forms of apparatus. The particular num-

ber of operations employed, and the particular character of the apparatus may obviously be varied, depending somewhat upon the thickness of the wall of the bearing as well as the material, and upon the degree of accuracy of production desired. The particular operations of the example referred to are as follows:

The embryo structure is first subjected to a bending action, the particular apparatus employed being indicated in Figs. 5 to 7 inclusive, in which 15 indicates a frame having guides 16 within which are reciprocatively mounted three shaping dies 17, 17^a and 18, the dies 17 and 17^a being substantially aligned and having their operating faces opposing each other; these operating faces are adapted to be opposite the parting line edges of the bearing when the latter is in position in the apparatus, these faces being formed on an arc corresponding concentrically with the opposing portions of the operating face of an anvil member 19, shown more particularly in Fig. 7. Die member or block 18 has its movements in directions 75 transverse to those of dies 17 and 17^a, and has an operating face of greater length than either of said dies, said operating face being curved on an arc which conforms substantially to that of dies 17 and 17^a. 80

Each of the dies 17, 17^a and 18 is adapted to be moved inwardly by suitable means, the drawings indicating this means as in the form of operating levers 20 having cam faces adapted to operate against the rear faces of 100 the dies, this arrangement being such as to permit of the application of pressure on to the embryo formation when the latter is seated external of the active face of the anvil 19. 105

The structure thus described is designed to effect a change in the embryo formation in the direction of shortening the inner and outer radii of the embryo formation. Since the embryo formation was of bronze and Babbitt lined, the arrangement was such as to tend to set up a change in the shape of the embryo formation and this was provided by attempting to change the general diameter dimensions to radii less than those of the desired article, the change being controlled more or less by the particular dimensions and configurations of the active face of anvil 19; for reasons presently pointed out, this face was given a more or less special configuration as indicated in Fig. 7. As shown in said figure the general center (x^3 , Fig. 7) of the active face configuration is located on a line x extending parallel to and spaced from an edge x^4 of the anvil, and the distance from said center to said face on said line has a length which corresponds to the radius of an arc forming the portion of said face at the extremes of such line, this radius being shown as 1.279 in.; the 110 115 120 125 130 135

same radius is used for that portion of the active face corresponding to an arc bisected by a line x' extending perpendicular to line x from center x^3 , so that at points of the face corresponding to the ends of line x and at a point on the active face intersecting line x' the arcs described have the same radius; these particular points are those directly opposite the active faces of dies 17, 17^a and 18. As will be seen, however, the active face of anvil 19 has two arcs of increased radius spaced from each other by the arc of line x' , the spacing being such that radii (indicated at x^2) which approximately bisect the arcs, will extend at right angles to each other (approximately) and practically bisect the right angles formed by the lines x and x' ; the increase in radius will be shown from the fact that these particular radii are 1.281 inches. These portions of larger radius are blended into the portions of less radius. The active face is thus made up of arcs having the radius of lines x and x' spaced apart by arcs having the radius of lines x^2 , the arcs being more or less blended together.

When, therefore, pressure is applied to the three actuating members 20—those for dies 17 and 17^a being preferably actuated in advance of that of die 18—the embryo formation will be sprung in the direction of shorter diameters (the active faces of the three dies having radii based on a diameter of 2.932 in.), setting of the cam levers 20 to apply the springing pressure will thus temporarily spring the embryo formation to a basis of smaller diameters and tend to slightly deform the angular direction of length from that of a true circle, due to the small difference in radii of the anvil. By first springing in the ends through the action of dies 17 and 17^a, a bending effect is first produced at the central portion of the embryo formation, after which the application of pressure through die 18 acts to correct the deformation at this point by forcing the ends (parting line) inward through a bodily advance of these portions between the opposed faces and the anvil and the dies.

This bending operation with its partial deformation of the embryo formation is of short duration, the dies being opened, thus releasing the embryo structure from the pressure. When the pressure is released there is a spring back of the middle of the embryo bearing toward its original shape and size, but this is only partial, leaving the bent structure approximately of the desired dimensions, the curved length of the bearing, however, being slightly deformed for the reasons heretofore pointed out. As will be understood, the fact that the radius or radii of the inner and outer faces of the bearings having been changed to decrease the length of such radii, and this action has

not been effective in shortening the curved length of the bearings, it will be obvious that the result has been to take up all or a major portion of the loss produced by the dividing operations of the blank, so that the parting line is approximately such as to more or less mate the similar face of a complementary bearing member without the necessity for the use of a shim.

The embryo formation thus produced is then subjected to the action of a shaping structure of suitable type, one form of which is disclosed in Figs. 8 to 11. This apparatus includes a body portion 21 having a recess 21^a carrying the exact curvature of the outer face of the finished bearing member—in the particular example shown, this face extends on a radius of 1.5 inches; the recess extends throughout one dimension of the body portion 21, and the latter has a face 85 adapted to receive a complementary face of a member 22, the latter having a block or anvil 23 having a curved face, the curvature of which corresponds to that of the inner face of the bearing member—for instance, it may be drawn on a radius of 1.3145; block 23 is so positioned that when body portion 21 and the member 22 are properly located in respect to each other, the curved faces of recess 21^a and that of block 23 will be concentric, the two members being spaced apart a distance to provide a semi-circular space therebetween corresponding to the thickness of the wall of the bearing member. The body portion 21 and the member 22 are detachably engageable through suitable means, the particular arrangement shown being that of a pair of pivoted bolts 24 adapted to swing to and from a position in advance of member 22 as shown in Fig. 8. This arrangement permits the two members to be drawn together after the embryo bearing has been placed in position between the curved faces, tightening of the studs or bolts 24 applying pressure in such manner as to correct any inaccuracy or deformation which was produced when operating in the bending apparatus previously described.

As a result, the bearing member will be accurately shaped to a true semi-cylindrical formation without affecting either the inner or outer faces of the member or materially affecting the skin effect produced before dividing the original blank. While the deformation of the blank may not be present in every instance, it is generally the case that there is more or less springing of the member in giving it the shape desired by the apparatus just described, so that when the members 21 and 22 have been moved to their closed positions, there is likely to be a strained condition of the member. And since the finished member must have the shape provided by the opposing faces of these members, it is necessary that this

strained condition be relieved in order that the bearing may retain this particular shape. This result is obtained by setting the metal of the bearing, an operation which may be 5 provided in different ways, one of which is shown in these figures 8 to 11 and which is now described.

25 indicates a plate secured to one face of body portion 21, this plate being shown 10 in plan view in Fig. 11. This plate 25 is provided with several openings 25^a arranged at spaced apart points on a curved line having a radius substantially that of an intermediate radius between the radii of the 15 inner and outer faces of the bearings in finished form—in the particular example shown, this radius is one and thirteen thirty-seconds inch, and one of the openings is shown as located at a point substantially 20 midway of the curved length of the bearing, two other openings being located at points adjacent the opposite ends of the bearings. These openings are adapted to receive pins 26 yieldably supported on springs 27 as 25 shown in Fig. 9, the arrangement being such that the pins project upwardly into the space between the opposing faces of the body portion 21 and block 23 and form a rest or support for the embryo bearing 30 which is positioned between the faces, thus locating one longitudinal end of the bearing on the pins and spaced from the plane of the face of plates 25.

The body portion 21 has the length of its 35 recess greater than the length of the bearing, so that when the latter is positioned between the opposing faces, and supported on pins 26, the opposite end of the bearing will be spaced from the opening formed by the 40 opposing faces 21^a and of block 23. Into this space thus left is placed a member 28 which forms a punch and practically conforms to the contour of the bearing in its 45 angular dimensions, the member 28 having a length to project from the assembled members.

The assembly is then placed in a suitable 50 press and pressure applied on the projecting portion of member 28, this pressure serving to move the member 28 and the bearing portion which is in advance of it toward the 55 face of the plate 25, pins 26 yielding under the pressure. This movement continues until the opposing end of the bearing comes in contact with the face of the plate 25 when the advance of the bearing is, of course, checked and the continued application of the pressure produces the setting action. The pressure applied is preferably, although 60 not essentially, on the order of a blow or hammer effect, produced for instance, by the effect of the check in the movement of the bearing provided when the advance end of the bearing contacts with plate 25; this check 65 in advance movement, while the pressure

applying member is still attempting to advance, subjects the blank to the action of opposing forces at its opposite ends, these forces being suddenly applied through checking action. And this becomes of ad- 70 vantage where the opposing forces are made active by the movement of the bearing itself, since the forces thus become active more or less in directions corresponding in lines connecting the points of application of 75 forces, the sudden jar or blow tending to bring about such molecular changes as may be necessary in order to "set" the bearing to the shape desired.

This hammer blow effects can be produced 80 by placing the assembly on the support of a press in the path of travel of a reciprocating member and in position so that the latter will contact with the projecting portion of member 28 as the reciprocating member is 85 approaching its extreme of travel in one direction. As the approach continues the bearing is being moved within the assembly and contact with plates 25 can be had just prior to the time when the extreme position is 90 reached; for instance, if the reciprocations are provided by a pitman, the contact would be had just prior to the time when the latter is crossing its dead center, thus making it 95 possible to control the power of the blow to any desired extent through varying the particular time in the travel of the pitman when initial contact is had. This control is of advantage in that it is not designed to provide a pressure or blow which will change 100 the shape of the bearing itself, the purpose of the blow effect being simply to sufficiently jaw the bearing and to set up the necessary molecular action as to relieve the strain placed upon the bearing by the closing of 105 the members 21 and 22, the pressure being applied in non-radial directions at the time the blow is imparted.

While I have not herein specifically shown 110 an apparatus for the purpose, it will be readily understood that the apparatus of Figs. 8 to 11 can be changed in a simple manner so as to permit of placing the blow on the edges which correspond to the parting line of the bearing, the arrangement being such that the two edges would be given a blow simultaneously and this would be communicated in angular directions through the bearing, the blow likewise being delivered in non-radial direction.

115 While I have specifically pointed out the bending of the embryo structure in advance of what may be termed the swaging operation, it will be understood that in some instances, for example where the bearing is 120 of thin wall section and of certain metals, the bending step may be omitted and the entire shaping operation be through the use of the swaging apparatus. It is generally 125 preferred, however, to apply the bending 130

step where extreme accuracy in the bearing is desired.

Obviously, the particular mechanisms disclosed are simply illustrative of various ways 5 of carrying out the methods, so far as mechanisms are concerned, and the invention is not limited in any way by the particular structure employed in carrying out the methods

10 The bearing structure produced by the methods herein referred to is substantially completed, the finishing having no effect on the general characteristics of the article. For instance, it is the practice in producing 15 the bearing for the Liberty motor referred to, to subject the product resulting from the swaging action to an operation for finishing the parting line, and after which the product is drilled, filleted and burred, these being 20 well known operations.

From the above, it will be readily understood that the product carries a number of characteristics which are more or less individual to itself. For instance, the body portion 25 is of the softer metal group, as for instance bronze; the Babbitt lining is practically uniform in thickness and may be of small cross section without affecting the ability to produce the article or rendering 30 the latter inefficient in operation; since the wall thickness is produced while the bearing is an integral part of the blank, its faces are truly curved, and the operations on the bearing after it has been divided out of the 35 blank does not materially affect these faces, the several operations tending to improve the texture and skin effect of the faces and at the same time eliminate any deformations which may have been produced in an 40 intermediate stage operation; the shaping to the proper size is by pressure action, with the operation or operations so arranged as to produce a proper molecular formation with the bearing in an accurate contour, this 45 molecular formation being made permanent while the bearing is in a more or less strained relation, so that the set of the metal will retain the structure in its proper condition, requiring positive strain in different 50 directions in order to affect the accuracy of the bearing itself. In other words, the embryo formation is strained or stressed to the desired dimensions, and while under such strain or stress is subjected to such action as 55 will produce the molecular formation necessary to retain it in such condition.

While I have herein disclosed ways in which the invention may be carried out, it will be readily understood that changes and 60 modifications therein may be required or desired in meeting the exigencies of use and I do not limit myself thereto but reserve the right to make any and all such changes or modifications therein as may be found necessary or desirable in so far as the same may 65

fall within the spirit and scope of the invention as expressed in the claims when broadly construed.

What I claim is:—

1. In the art of producing bearings, bushings, etc., the method of producing the article which consists in producing a tubular blank having its walls corresponding in thickness to that of the completed article and having its inner and outer faces of greater radii than the corresponding radii of such completed article, then dividing the blank diametrically to produce a pair of embryo articles, and completing the article by reducing the radii of such inner and outer faces by pressure application and applying a setting action thereto when the shape and radii dimensions substantially correspond to the similar characteristics and dimensions of the completed article. 70

2. In the art of producing bearings, bushings, etc., the method of producing the article which consists in producing a tubular blank of circular contour, treating the blank to provide a wall thickness corresponding to that of the completed article and having its inner and outer faces of greater radii than the corresponding radii of such completed article, then dividing the blank diametrically to produce a pair of embryo articles, and completing the article by reducing the radii of such inner and outer faces by pressure application and applying a setting action thereto when the shape and radii dimensions substantially correspond to the similar characteristics and dimensions of the completed article. 90

3. In the art of producing bearings, bushings, etc., the method of producing the article which consists in producing a tubular blank with a Babbitt lining and having its wall corresponding in thickness to that of the completed article with its inner and outer faces of greater radii than the corresponding radii of such completed article, then dividing the blank diametrically to produce a pair of embryo articles, and completing the article by reducing the radii of such inner and outer faces by pressure application and applying a setting action thereto when the shape and radii dimensions substantially correspond to the similar characteristics and dimensions of the completed article. 105

4. In the art of producing bearings, bushings, etc., the method of producing articles which consists in producing a tubular blank having its wall corresponding in thickness to that of the completed article and having its inner and outer faces of greater radii than the corresponding radii of said completed article, then dividing the blank diametrically to produce a pair of embryo articles, and shaping the article to reduce the radii of such inner and outer faces by strain- 125

- ing the embryo article in angular direction to place its faces on the desired radii, and subjecting the article to a sudden impact while undergoing strain.
5. In the art of producing bearings, bushings, etc., the method of producing articles which consists in producing a tubular blank having its wall corresponding in thickness to that of the completed article and having its inner and outer faces of greater radii than the corresponding radii of said completed article, then dividing the blank diametrically to produce a pair of embryo articles, and shaping the article to reduce the radii of such inner and outer faces by straining the embryo article in angular direction to place its faces on the desired radii, and subjecting the article to a sudden impact while undergoing strain, with the direction of impact exerted non-radially.
6. In the art of producing bearings, bushings, etc., the method of producing articles which consists in producing a tubular blank having its wall corresponding in thickness to that of the completed article and having its inner and outer faces of greater radii than the corresponding radii of said completed article, then dividing the blank diametrically to produce a pair of embryo articles, and shaping the article to reduce the radii of such inner and outer faces by straining the embryo article in angular direction to place its faces on the desired radii, and subjecting the article to a sudden impact while undergoing strain, with the direction of impact exerted longitudinally of the article.
7. In the art of producing bearings, bushings, etc., the method of producing articles which consists in producing a tubular blank having its wall corresponding in thickness to that of the completed article and having its inner and outer faces of greater radii than the corresponding radii of said completed article, then dividing the blank diametrically to produce a pair of embryo articles, and shaping the article to reduce the radii of such inner and outer faces by straining the embryo article in angular direction to place its faces on the desired radii, and subjecting the article to a sudden impact while undergoing strain, with the impact exerted in a direction corresponding to the direction of axis of the article.
8. In the art of producing bearings, bushings, etc., the method of producing articles which consists in producing a tubular blank having its wall corresponding in thickness to that of the completed article and having its inner and outer faces of greater radii than the corresponding radii of said completed article, then dividing the blank diametrically to produce a pair of embryo articles, and shaping the article to reduce the radii of such inner and outer faces by straining

the embryo article in an angular direction to place its faces on the desired radii, and subjecting the article to a hammer blow while undergoing strain, said blow being exerted in the direction of the axis of the article.

9. In the art of producing bearings, bushings, etc., the method of producing articles which consists in producing a tubular blank having its wall corresponding in thickness to that of the completed article and having its inner and outer faces of greater radii than the corresponding radii of said completed article, then dividing the blank diametrically to produce a pair of embryo articles, shaping the article to reduce the radii of such inner and outer faces by straining the embryo article in an angular direction to place its faces on the desired radii, and subjecting the article to a hammer blow while undergoing strain, said blow being exerted in the direction of the axis of the article, and exerted at the opposite ends of the article.

10. In the art of producing bearings, bushings, etc., the method of producing articles which consists in producing a tubular blank having its wall corresponding in thickness to that of the completed article and having its inner and outer faces of greater radii than the corresponding radii of said completed article, then dividing the blank diametrically to produce a pair of embryo articles, shaping the article to reduce the radii of such inner and outer faces by straining the embryo article in an angular direction to place its faces on the desired radii, and subjecting the article to a hammer blow while undergoing strain, with the blow exerted in a non-radial direction and applied at opposing edge portions of the article.

11. In the art of producing bearings, bushings, etc., the method of producing the article which consists in producing a tubular blank having its wall corresponding in thickness to that of the completed article and having its inner and outer faces of greater radii than the corresponding radii of the completed article, then dividing the blank diametrically to produce a pair of embryo articles, and completing the article by successively applying a spring set to the article in the direction of final dimensions and in straining the sprung article to its true radii dimensions, and applying a blow effect to the article while under such strain.

12. In the art of producing bearings, bushings, etc., the method of producing the article which consists in producing a tubular blank having its wall corresponding in thickness to that of the completed article and having its inner and outer faces of greater radii than the corresponding radii of the completed article, then dividing the blank diametrically to produce a pair of em-

- bryo articles, and completing the article by successively applying a spring set to the article in the direction of final dimensions and in straining the sprung article to its true radii dimensions, and applying a blow effect to the article while under such strain, with the blow delivered in a direction to be ineffective to change the thickness of the article wall.
- 10 13. In the art of producing bearings bushings, etc., the method of producing the article which consists in producing a tubular blank having its wall corresponding in thickness to that of the completed article and having its inner and outer faces of greater radii than the corresponding radii of the completed article, then dividing the blank diametrically to produce a pair of embryo articles, and completing the article
- 15 20 by successively applying a spring set to the article in the direction of its curved length and straining the sprung article to its final true radii dimensions, and applying a blow effect to the article while under such strain.
- 25 14. In the art of producing bearings, bushings, etc., the method of producing the article which consists in producing a tubular blank having its wall corresponding in thickness to that of the completed article
- 30 35 and having its inner and outer faces of greater radii than the corresponding radii of the completed article, then dividing the blank diametrically to produce a pair of embryo articles, and completing the article
- 40 45 by applying a bending strain to the article in the direction of its curved length to produce a spring set thereto, applying a pressure application to the sprung article to strain it to its true radii dimensions, and
- 50 applying a blow effect to the article while under such strain.
15. In the art of producing bearings, bushings, etc., the method of producing the article which consists in producing a tubular blank having its wall corresponding in thickness to that of the completed article and having its inner and outer faces of greater radii than the corresponding radii of the completed article, then dividing the blank diametrically to produce a pair of embryo articles, and completing the article by applying a bending strain to the article

in the direction of its curved length to produce a spring set thereto, applying a pressure application to the sprung article to strain it to its true radii dimensions, and applying a blow effect to the article while under such strain, with the blow impact delivered in non-radial direction.

16. In the art of producing bearings, bushings, etc., the method of producing the article from an embryo blank having its wall corresponding in thickness to that of the completed article and having its inner and outer faces of greater radii than the corresponding radii of the completed article, the steps which consist in completing the article by reducing the radii of such inner and outer faces by pressure application and applying a setting action thereto when the shape and radii dimensions substantially correspond to the similar characteristics and dimensions of the completed article.

17. In the art of producing bearings, bushings, etc., the method of producing the article from an embryo blank having its wall corresponding in thickness to that of the completed article and having its inner and outer faces of greater radii than the corresponding radii of the completed article, the steps which consist in shaping the embryo article to reduce the radii of such embryo article in angular direction to place its faces on the desired radii, and subjecting the article to a sudden impact while under strain.

18. In the art of producing bearings, bushings, etc., the method of producing the article from an embryo blank having its wall corresponding in thickness to that of the completed article and having its inner and outer faces of greater radii than the corresponding radii of the completed article, the steps which consist in successively applying a spring set to the embryo article and in straining the sprung article to its true radii dimensions, and applying a blow effect to the article while under such strain.

In testimony whereof I affix my signature in the presence of two witnesses.

LEES W. CHADWICK.
